C. C. Woody

By *Clarence A. O'Brien*

Attorney

UNITED STATES PATENT OFFICE.

CLYDE C. WOODY, OF WINONA, MINNESOTA, ASSIGNOR TO MADISON SILO COMPANY,
OF WINONA, MINNESOTA.

SILO.

Application filed April 5, 1926, Serial No. 99,949. Renewed April 18, 1927.

My present invention pertains to silos and consists in the door fastening step affording means possessed of the practical advantages hereinafter ascribed to the same.

With the foregoing in mind, the invention in all of its details will be fully understood from the following description and claims when the same are read in connection with the drawings, accompanying and forming part of this specification, in which:—

Figure 1 is an elevation showing a silo embodying the preferred form of my invention.

Figure 2 is an enlarged fragmentary perspective showing one of the door openings and the door complementary thereto and also showing the door fastening and step affording means of my invention.

Similar numerals of reference designate corresponding parts in both views of the drawings.

The silo illustrated and designated by 1 is shown as formed of concrete, Figure 2, and is characterized by a vertical series of spaced door openings 2. Interiorly the silo is provided with rabbets 3 about the door openings 2 and in the rabbets 3 are removably arranged doors 4 which may be of any material compatible with the purpose of my invention. The said invention contemplates the displacement of the doors 4 inwardly.

In accordance with my invention, each of the doors 4 is provided with two steps 5, the said steps being formed of metal and being fixed at their ends to the face of the door 4 and being provided with intermediate portions spaced from the face of the door. From Figure 1 it will be understood that the steps 5 extend in series practically through the height of the silo, and that by virtue of the steps or step bars 5 being fixed in horizontal position to the doors 4, and the doors 4 being seated in and on and supported by the silo wall, a strong and safe ladder is afforded from a point adjacent to the bottom of the silo to a point adjacent to the top thereof. In combination with each door 4 and each pair of steps or step bars 5, I employ fastener means, the said means being made up of a lever member 6 pivoted at 7 to the upper step or step bar, and a link member 8 pivoted at 9 to the lower arm of the lever 6 and longitudinally slotted at 10 and connected to the lower step or step bar 5 by a pintle 11 which extends through the

said slot 10. The outer ends of the lever 6 and link 8 are preferably flared, Figure 2, so as to readily move into engagement with the outer side of the silo 1.

Manifestly with the parts arranged as shown in Figure 2, the door 4 will be strongly supported in the silo 1 and will be securely and tightly fastened in closed position, and when the bars 5 are used as steps it will be noted that there will be no liability of any casual unfastening of any one of the doors taking place. This latter is due in large measure to the fact that lateral movement of the lever member 6, i. e., movement of the upper arm of said lever member 6 toward the right or the left is necessary to the disengagement of the outer ends of the lever member 6 and link 8 from the silo 1 so that said end will clear the walls of the openings when the door is displaced or removed inwardly as before suggested, and there is no liability of said lateral movement of the lever member 6 being accidentally brought about.

It will also be noted that for the fastening of the door shown in Figure 2, it is simply necessary to seat the door 4 in the rabbet 3 and then swing the lever member 6 to the upright position shown when said lever member 6 and the link 8 will engage the outer side of the silo above and below the opening 2 with the result that the door will be strongly and securely held in closed position.

It will be apparent from the foregoing that the several doors 4 are held in place due to pressure between the fastening means and the door frame or silo 1; also, that my novel construction is simple and inexpensive, the steps or step bars 5 are entirely independent of the latch or door fastening means, and that by virtue of the two steps on each door it is practicable to form a continuous ladder, Figure 1, with the steps uniformly spaced and so that there is no necessity of using any part of the silo or any part of the latching means of the several doors for steps. On the other hand the steps or step bars 5 are rigidly affixed to the doors 4 with the result that the ladder as a whole is rendered safe and strong.

I have entered into a detailed description of the construction and relative arrangement of the parts embraced in the present and preferred embodiment of my invention in order to impart a full, clear and exact understanding of the said embodiment. I

2
do not desire, however, to be understood as limiting myself to the structure as illustrated and explicitly described, my invention being defined by my appended claims 5 within the scope of which modifications may be made without departure from my invention.

Having described my invention, what I claim and desire to secure by Letters Patent, is:—

1. The combination of a silo having a door opening, a door positioned to close said opening and removable inwardly, horizontal steps fixed to the face of the door at the 15 ends of the steps and spaced apart and having intermediate portions spaced from the face of the door, and upright fastening means for the door connected with the steps thereof and arranged to cooperate with the 20 outer side of the silo in tightly holding the door in closed position; the fastening means of the door comprising a lever member pivotally connected at an intermediate point of its length to the intermediate portion of one 25 step and extending above and below the

same, and a link pivotally connected to the said lever member and longitudinally slotted and connected to the other step by means extending through said slot and extending above and below said step.

2. In combination, a silo having a door opening, a door positioned to close said opening and removable inwardly, spaced steps fixed adjacent to their ends to the face of the door, and upright fastening means 35 carried by said steps and arranged to detachably engage the outer side of the silo above and below the door opening.

3. In combination, a silo having a door opening, a door positioned to close said 40 opening and removable inwardly, spaced steps fixed adjacent to their ends to the face of the door, and upright fastening means carried by said steps and arranged to detachably engage the outer side of the silo 45 above and below the door opening; the said fastener means comprising members flared at their outer ends.

In testimony whereof I affix my signature.
CLYDE C. WOODY.
